DESIGN FOR AN ELECTRIC SHAVER HOLDER

Albert E. Hutt, Stamford, Conn., and Carl L. Otto,
New York, N. Y., assignors to Schick Incorporated,
a corporation of Delaware

Application December 19, 1945, Serial No. 124,873

Term of patent 14 years

(Cl. D4—3)

To all whom it may concern:

Be it known that we, Albert E. Hutt and Carl L. Otto, citizens of the United States and residents of Stamford and New York, in the counties of Fairfield and New York and States of Connecticut and New York, respectively, have invented a new, original, and ornamental Design for an Electric Shaver Holder, of which the following is a specification, reference being had to the accompanying drawing, forming a part thereof.

Fig. 1 is a perspective view of the electric shaver holder embodying the new design;

Fig. 2 is a top plan view of the same on a slightly reduced scale; and

Figs. 3 and 4 are, respectively, front and side elevational views of the holder, on the same scale as Fig. 2.

We claim:

The ornamental design for an electric shaver holder, as shown.

ALBERT E. HUTT.
CARL L. OTTO.
